Patented Jan. 3, 1928.

UNITED STATES PATENT OFFICE.

ROBERT E. McELDOWNEY, OF NEW MARTINSVILLE, WEST VIRGINIA, ASSIGNOR TO NEW MARTINSVILLE GLASS MFG. CO., OF NEW MARTINSVILLE, WEST VIRGINIA, A CORPORATION OF WEST VIRGINIA.

DESIGN FOR A DECANTER.

Application filed October 22, 1927. Serial No. 23,849. Term of patent 3½ years.

To all whom it may concern:

Be it known that I, ROBERT E. McELDOWNEY, a citizen of the United States, residing at New Martinsville, in the county of Wetzel, State of West Virginia, have invented a new, original, and ornamental Design for a Decanter, of which the following is a specification, reference being had to the accompanying drawing, forming part thereof.

I claim:

The ornamental design for a decanter, as shown.

ROBERT E. McELDOWNEY.
